Application November 21, 1945, Serial No. 630,069

8 Claims. (Cl. 200—26)

1

This invention relates to electrical switches and particularly to distributor switches for ignition systems.

An object of the invention is to improve the construction of electrical switches and distributors.

Other objects of the invention will be apparent from the following description and accompanying drawings taken in connection with the appended claims.

The invention comprises the features of construction, combination of elements, arrangement of parts, and methods of manufacture referred to above or which will be brought out and exemplified in the disclosure hereinafter set forth, including the illustrations in the drawings, the scope of the invention being indicated in the appended claims.

In the drawings:

Figure 1 is a front view of a distributor switch embodying the principles of this invention with parts broken away to show the detailed features of construction;

Figure 2 is a sectional view taken along the line 2—2 of Figure 1;

Figure 3 is an enlarged view of a portion of the distributor switch shown in Figure 1;

Figure 4 is a sectional view taken along the line 4—4 of Figure 3;

Figure 5 is a sectional view of the roller used in the distributor shown in Figure 1; and

Figure 6 is a diagrammatic view illustrating a modification of the invention.

This invention is principally concerned with an electrical switch construction for successively making a plurality of electrical contacts. Such a switch is particularly useful in ignition systems for operating the spark plug circuits of an engine in proper sequence as well as in various other applications such as the control of electric signs, testing circuits and the like.

While a preferred embodiment of the invention is described herein, it is contemplated that considerable variation may be made in the method of procedure and the construction of parts without departing from the spirit of the invention. In the following description and in the claims, parts will be identified by specific names for convenience, but they are intended to be as generic in their application to similar parts as the art will permit.

Distributor switches previously constructed have oftentimes utilized a rotatable contact brush which passes over a track, suitable contacts being spaced at intervals along the track

2

for engagement by the brush. In such systems, the brush alternately engages the contacts and the insulated portions of the track which necessarily have different elastic properties. Accordingly, the difference in compliance between the two materials tends to cause oscillation or bouncing of the brush or contact arm as it moves around the track resulting in rapid and uneven wear of the distributor parts. In accordance with 5 this invention, a contact roller is provided which rides upon a continuous smooth track of wear-resistant material thus insuring smooth operation of the distributor and freedom from oscillation or bouncing. The contact roller successively engages a plurality of sets of contacts as it travels around the track, each set comprising a pair of contacts disposed at opposite sides of the track and adapted to be bridged by the roller. Although these contacts initially protrude inwardly beyond the track surface to a slight extent, the roller works the contacts down until, after a short period of operation, they are at substantially the same level as the circular track. At this time, the contacts are still in 10 position to be engaged by the roller but the pressure of the roller on the contacts is very small so that the wear thereon is greatly decreased. An additional feature of the invention resides in the fact that the contacts are mechanically separated from the track and from each other so that there is little or no danger of metallic particles becoming lodged in the track which might affect the timing of the distributor or cause bouncing.

15 The distributor type switch of this invention is particularly useful in high-frequency ignition systems wherein voltages as high as 1,200 volts are often used. The novel track and contact arrangement affords ample contact area for reliable operation and sparking is substantially eliminated with resultant freedom from radio noise interference.

20 Referring now to the drawings in detail, the distributor type switch may comprise a supporting structure 10 which includes an inner circular wear-resistant track 11. The track is preferably formed from a suitable insulating compound having high resistance to wear, such for example, as Bakelite. The structure 10 may be 25 flanged as at 12 to provide shoulders at the respective opposite sides of the track for accommodating contact members in the manner hereinafter described. Annular plates 13 and 14 of insulating material are secured in any suitable 30 manner to the supporting structure 10, the cen-

tral openings in said plates being of greater diameter than the track 11. The plates 13, 14 carry a plurality of contact sets 15 which are preferably spaced at equal intervals around the track 11. Each set comprises a pair of spring fingers or contacts 16, 17 which are supported, respectively, by the plates 13 and 14. A contact portion 18 of each finger extends inwardly toward the track 11 and is closely spaced with respect to the adjacent shoulder 12 and the track. Each contact 16 may be connected to a suitable terminal or binding post 19 which, in turn, may extend to a spark plug excitation circuit or any other circuit to be energized. The contacts 17 may be interconnected by a conductor plate 19 interposed between said contacts and the insulation member 14 and this plate may be provided with a terminal or binding post 19' for connection to an external circuit. The use of the plate 19 is optional, however, as it will be apparent that each contact 17 may be provided with a separate terminal connection, if desired. As shown best in Figure 4, the contact portion 18 initially protrudes inwardly of the track 11 for a short distance for a purpose to be hereinafter explained.

The switching mechanism is driven by a shaft 25 which may be suitably connected to the drive shaft of an engine or to any other switch-actuating device. An arm 26 fixed on the shaft 25 has a roller carriage 27 pivoted thereto as at 28. A roller 29 is journaled in the carriage and urged into engagement with the track 11 by a spring 30 which is suitably secured to the arm 26 and the carriage 27. The roller 29, as best shown in Figure 5, comprises a ring or cylinder 35 of conductive material which is adapted to successively bridge the fingers 16, 17 of each contact set as the roller travels around the track. The cylinder 35 is fixed on a pair of complementary sleeves 36, 37 of Bakelite or other insulating material which define a cylindrical passage within which is inserted a tube 38 of hardened metal. Suitable needle bearings 39 may be provided at the opposite ends of the tube in order to journal the roller in the carriage 37.

As the shaft 25 is rotated, the roller 29 successively engages and bridges the contact sets 15 to thereby close the circuits associated therewith. As previously stated, the contact portions 18 initially protrude inwardly beyond the track. After a short period of operation, the contact portions 18 are worked down until they extend inwardly of the track only a sufficient distance to be contacted by the roller 29. When the contacts are in this position, the roller exerts very little force thereon during operation of the distributor so that the wear on the contacts is greatly decreased. I indicate this relative position of the contact portions and the track by the phrase "substantially level" in the appended claims. The described construction has the advantage that the contacts may be made of ductile material so that wearing away of the contact surface is substantially eliminated while the surface of the track may be formed from hard wear-resistant material so that it can withstand the operation of the roller. Moreover, it will be apparent that a smooth continuous surface is provided for on the roller so that bouncing or oscillation thereof with resultant faulty operation of the distributor is avoided.

In the modification of the invention shown in Figure 6, a sliding contact 40 rather than a roller is utilized for engaging and bridging the contact

sets 15. The contactor is supported by a leaf spring 41 from an arm 42 which is suitably attached to the drive shaft. Consequently, the spring urges the contact 40 into engagement with the track, the modified form operating in substantially the same manner as the apparatus shown in Figure 1 when the driveshaft is rotated.

In some cases, a common connection to the contacts may be made through the shaft and roller assembly. In such a construction, the contacts at one side of the device may be eliminated and the roller construction modified so that the current passes through the shaft and the roller to successively energize the contacts at the other side of the switch. It will be apparent that the construction may be modified so that the contacts and the circular track are disposed in a common plane, if desired, with the contacts of each set being disposed in radial alignment at opposite sides of the track.

While the present invention, as to its objects and advantages, has been described herein as carried out in specific embodiments thereof, it is not desired to be limited thereby but it is intended to cover the invention broadly within the spirit and scope of the appended claims.

What is claimed as new and desired to be secured by Letters Patent is:

1. In a switching device for successively closing a plurality of contacts, a circular track having an inner insulative wear-resistant surface, a rotatable contact assembly comprising a roller centralized with respect to said track adapted to travel on said wear-resistant surface, a spring member for urging said roller into engagement with said surface, and a plurality of contact sets spaced at equal intervals around the track on opposite sides thereof, each set comprising a pair of resilient contact members disposed at opposite sides of the track, each contact member having an arcuate portion adjacent and at substantially the same level as the track for engagement with said roller as it rotates around the track.

2. In a distributor for successively closing a plurality of spark plug circuits, a circular track having an inner wear-resistant and non-conducting surface, a rotatable contact assembly comprising a roller centralized with respect to said track adapted to travel on said wear-resistant surface, and a plurality of contact sets spaced around the track, each set comprising a pair of contacts disposed at opposite sides of the track, each contact comprising a resilient portion protruding inwardly of the track for engagement with the roller, said inwardly-protruding portions becoming substantially level with the surface of the track after a period of operation of said distributor whereby the pressure of the roller on the contacts is negligibly small as compared to the centrifugal force of the roller against the surface of the track.

3. In a distributor for successively closing a plurality of spark plug circuits, a circular non-conductive track, a plurality of contact sets spaced around said track, each set comprising a pair of contacts disposed at opposite sides of the track on opposite sides thereof, each contact having a conductive surface substantially level with the surface of the track at all times, and a contactor adapted to travel around the track to successively engage and bridge the contact sets, the portion of the track which is engaged by the contactor having a smooth wear-resistant surface of an immovable nature to prevent bouncing

of the contactor thereon whereby substantially all the pressure exerted by said contact member is directed against said track and negligible pressure is exerted against said contacts.

4. In a distributor for successively closing a plurality of spark plug circuits, a circular insulating track, a plurality of contact sets spaced around said track, each set comprising a pair of contacts disposed at opposite sides of the track, each contact having a conductive surface protruding inwardly from the surface of the track, and a contactor adapted to travel around the track to successively engage and bridge the contact sets, the portion of the track which is engaged by the contactor having a smooth wear-resistant and insulating surface to prevent bouncing of the contactor thereon, said inwardly-protruding surfaces becoming substantially level with the surface of the track after a period of operation of said distributor whereby the pressure of the roller on the contacts is negligibly small as compared to the centrifugal force of the roller against the surface of the track.

5. In a distributor, a supporting structure comprising a circular track formed from wear-resistant material, a plurality of contacts spaced around said track on opposite sides thereof in equal numbers and adapted for connection to the respective energizing circuits of a plurality of spark plugs, said contacts being substantially level with the surface of said track, a contact member adapted to travel on said track and successively engage said contacts and bridge opposite ones to thereby energize said circuits, and means for supplying current to said contact member when it is in engagement with said contacts.

6. In a distributor, a supporting structure comprising a circular track formed from wear-resistant material, a plurality of contact sets secured to said structure and spaced around said track, each set comprising a pair of contacts disposed at opposite sides of the track, each contact having a portion which is substantially level with said track, the contacts at one side of the track being adapted for connection to the respective energizing circuits of a plurality of spark plugs, the contacts at the other side of the track being connected together whereby current may

be supplied to said interconnected contacts from a common source, and a contact roller adapted to travel on said track and successively bridge said contact sets to thereby energize said circuits, the pressure of the roller on the contacts being negligibly small as compared to the centrifugal force of the roller against the surface of the track.

7. In a distributor, a supporting structure comprising a circular track formed from insulating material, a plurality of contact sets secured to said structure and spaced around said track, each set comprising a pair of contacts disposed at opposite sides of the track, each contact having a portion which is substantially level with said track, a shaft at the center of said track having an arm thereon, a carriage pivoted on said arm having a roller journaled therein, and a spring member for urging the roller into engagement with said wear-resistant track, said roller being adapted to ride on the track as the shaft is rotated and successively bridge said sets of contacts.

8. In a switching device for successively closing a plurality of contacts, an inner track having a circular wear-resistant and insulative surface, a contact roller centralized on said track and adapted to travel on said surface, and a plurality of contact sets spaced around the track on opposite sides thereof in equal numbers, each set comprising a pair of ductile conductive contact members substantially level with the surface of the track, adapted to be bridged by said roller as it rotates around the track, the pressure of the roller on the contacts being negligibly small as compared to the centrifugal force of the roller against the surface of the track.
